ENGINE STARTING MECHANISM

Romeo M. Nardone, East Orange, N. J., assignor
to Eclipse Aviation Corporation, East Orange,
N. J., a corporation of New Jersey

Application October 2, 1930, Serial No. 486,026

3 Claims. (Cl. 74—7)

This invention relates to engine starting devices, and more particularly to devices for starting engines of the type wherein an explosive gaseous charge is employed as an energy supplying medium.

An object of the invention is to provide in a device of the foregoing character, novel means for securing an initial turning movement of the power shaft of the engine to be started.

10 Another object of the invention is to provide in a device of the foregoing character novel means for turning over the power shaft of the engine to be started at two or more different speeds.

A further object of the invention is to provide novel means for selecting which of two or more speed transmitting mechanisms is to be used to supply the initial torque for driving the engine.

Still another object is to provide means for accelerating the engine starting apparatus after the initial engagement of said apparatus with the member to be driven.

Still another object of the invention is to provide novel means for automatically rendering ineffective the initial driving connections after the initial turning movement has been transmitted to the member to be driven.

A further object is to provide novel speed increasing mechanism for multiplying the initial speed of rotation of the starting mechanism so as to transmit the turning power to the member to be driven at a speed most suitable for the performance of the desired function.

Another object of the invention is to provide a comparatively simple, efficient and reliable apparatus for the purposes stated, and in which a saving of electric motive power can be effected.

A further object is to provide an invention of the foregoing character which may be readily accessible for inspection or replacement of parts.

Other objects and advantages to be derived from the use of the novel mechanism constituting the present invention will appear from an inspection of the following specification with reference being had to the accompanying drawing wherein the embodiment at present preferred is shown by way of illustration of the invention.

It is to be expressly understood however that the drawing is for the purpose of illustration and description only, and is not designed as a definition of the limits of the invention, reference being had for this purpose to the appended claims.

55 In the drawing, wherein like reference char-

acters refer to like parts throughout the several views.

Fig. 1 is a view in elevation, partly sectioned, of a mechanism embodying the invention; and

Fig. 2 is a transverse sectional view along the line 2—2 of Fig. 1.

Referring more particularly to the drawing, the embodiment of the invention illustrated comprises a drive proper including a driving member which is adapted to engage a member of the engine to be started, and also reduction means combined with such drive proper and operated in suitable manner and by suitable means such as an electric motor as herein shown.

First describing the drive proper, the same is located within the forward portion of casing 1 which is suitably supported as being detachably connected with the crankcase of the engine in suitable manner as by means of the flange 2; the rear portion being connected to the forward portion as shown at 3. Within a bushing 4 in the casing, there rotates a driving barrel 5 and a shell or nut 6 concentrically arranged therewithin and providing a considerable annular space between them to receive a yieldable driving connection which is here shown in the form of a friction clutch 7. This clutch is composed of two sets of clutch plates or disks which are splined respectively to the interior of the barrel and the exterior of the shell. The means preferably employed for exerting pressure upon these plates comprises a series of coil springs 8 located in a part of such annular space, their pressure being regulated by the adjustable nut 9 screwing onto the outer end of the shell or nut 6.

The nut 6 is preferably internally threaded to receive the corresponding threads of a screw shaft 10 which constitutes a main portion of the driving member whose other principal portion is an engaging head 11 splined or otherwise fixedly held to the shaft 10, and having angularly disposed jaws or teeth to engage corresponding jaws or teeth on the sleeve 12 which connects with the power shaft of the engine; the member 11 being frictionally held against rotation by ring clamping means 11a until such time as rotation of shell 6 is imparted to the member 10 to overcome the drag of spring member 11a. The inner end of the screw shaft is preferably provided with a stop nut 14.

As above stated, the nut 6 is formed as a shell to whose exterior one set of the clutch plates 7 is splined. The rear end of shell 6 is provided with a marginal flange 17 bearing against the annular

35

55

member 18 which in turn abuts the right-hand end of the clutch plates 7.

Next describing the reduction gearing, the same includes a rotatable gear 19 which is mounted on shaft 21 having its bearings in the hub of the gear 19 and also in the socket formed in the enlarged end 65 of shaft 22. The gear 19 drives the planetary gearing including the series of planetary pinions, one of which is shown at 26, and also including the parallel plates 27 and 28 which form a frame for such pinions and are held in place by the studs 30 on bearings 29. The stationary ring gear 23 is secured to the casing 1 by suitable means including the pins 24. The means for imparting the rotation of the planetary gears to the barrel 5 preferably takes the form of a series of riveted members 20.

The means for actuating the apparatus is here shown as an electric motor 31 whose armature shaft 22 is provided at its forward enlarged end 65 with a pinion 68 meshing with the gear 59, the latter being the driving means for pinion 39 and gear 19.

Describing a cycle of operation for the parts thus far enumerated, and assuming that the actuating means is the electric motor, when the motor is energized the shaft 22 will be rotated, thereby rotating the pinion 68, gear 59, pinion 39, gear 19 and the planetary gearing, and consequently rotating the driving barrel 5 to transmit torque through friction clutch 7 to the shell or nut 6. By reason of the rotation of this nut, the screw shaft or driving member 10, being held against rotation by members 11 and 11a, is automatically advanced longitudinally to the left, thereby projecting member 11 into engagement with the engine member 12. When such longitudinal movement ceases, the torque of the motor will be transmitted through the mechanism described to the member 11, thereby overcoming the frictional resistance to rotation, and cranking the engine.

From the foregoing it will be observed that the engine has been initially cranked through the force of the driving power transmitted through the shaft 22 and the gearing shown at 68 and 59, such gearing being preferably designed to supply the necessary torque to overcome the initial maximum resistance to turning inherent in the member 12. Since the gearing just referred to is adapted to supply maximum torque, it is an object of the present invention to provide supplementary speed multiplying mechanism whereby the considerably lessened resistance to rotation which is offered by the member 12 once the initial friction has been overcome, can be taken care of by a system of gears which will be capable of supplying such reduced torque at a considerably greater speed.

The present invention therefore discloses means for multiplying the speed and proportionately reducing the torque of the driving apparatus after the initial relatively great torque has been supplied at a considerably reduced speed through the initial driving connections above described. As shown herewith by way of illustration of the preferred means for effecting this result, the means employed comprises a suitable motion transmitting member 40 adapted to rotate with the gear 59 at all times, and therefore adapted to transmit power thereto when it is itself drivably associated with the primary driving member 22, said member 40 constituting one principal member of a clutch mechanism whose other principal member is shown at 41. Such

clutch mechanism may of course take any suitable form as will be obvious to persons skilled in the art, but as shown herewith by way of illustration, the mechanism preferably includes a driving jaw or plate having suitable teeth or other equivalent means 42 adapted to engage correspondingly disposed members 43 on the complementary driven member 40, the latter being rigidly secured to the shaft 44 by suitable key means such as that indicated at 45.

The means preferably employed for normally maintaining driving member 41 out of engagement with the member 40, and the associated means for effecting such engagement notwithstanding said preventing means comprises, as shown in Fig. 1 by way of illustration of the preferred arrangement, a spring or equivalent yielding member 46 having one end abutting the wall of housing 1 and having its central portion wound around a pin or other suitable pivot member 47 for rod 48, the opposite end of the spring 46 being so formed as to operatively engage the lower portion of rod 51 as indicated at 49.

From the foregoing it will be evident that the member 46 is adapted to exert a force against the member 48 tending to hold said member in the position indicated in Fig. 1 in which position it is adapted to maintain the member 41 out of driving relation to the member 40. The means whereby the member 48 controls longitudinal movement of the member 41 preferably comprises an annular groove 50 adapted to receive the enlarged end of the member 51 in such manner that a rocking motion imparted to the member 48 so as to cause it to rock upon its fixed pivot 47 will produce a corresponding longitudinal displacement of the member 41 to the left as viewed in Fig. 1 and therefore into driving engagement with the member 40. At 52 is shown a member intended to indicate any suitable device for permitting the operator of the engine to control movement of the rod 48 from any convenient location.

From the foregoing it will be apparent that means are provided for normally preventing a driving engagement between the members 41 and 40, therefore normally preventing the transmission of a driving force to gear 19 by way of gears 55 and 56 and shaft 54. It will be recalled however that the rotation of gear 68 during the transmission of the initial starting torque to the member 12 by means before described causes a rotation of gear 59, and hence of pinion 39 and gear 19, by virtue of the provision of the overrunning clutch member 66 which constitutes a positive driving connection between the bored end 65 of shaft 22 and the gear 68 (assuming clockwise rotation of member 65 as viewed in Fig. 2) so long as members 41 and 40 are out of engagement. This disengagement of the members 40 and 41, which normally obtains, renders rotation of the members 40 and 53 an idle nonproductive movement. That is to say, the end portion 53 of shaft 44 during the existing of the foregoing conditions, will rotate freely in the recess provided in the member 54 as shown. The member 54 will also rotate under the same conditions, its rotation being relative to the rotation imparted to the member 53 and at a different speed, rotation being imparted to the member 54 under such conditions by virtue of its connection with the gears 55 and 56, these gears being constantly in mesh, and the former being keyed to the enlarged portion 57 of shaft 22 by suitable means such as that indicated at 58.

From the foregoing it will be evident that the rotation of members 56 and 54 which is produced by the initial energization of the motor 31 will have no effect, from an operating standpoint, upon the speed or torque transmitted to the members 11 and 12, such initial speed and torque being determined by the design and relative arrangement of the members 68, 59, etc., together with the speed of rotation of the motor 31. After such initial transmission of a relatively great torque at a relatively low speed, however, a considerably reduced torque (preferably just sufficient to maintain a force capable of overcoming the normal drag of the engine as distinguished from the much greater initial inertia thereof) and a considerably increased speed can be produced by operation of the auxiliary transmission mechanism under the control of the operator of the engine by manipulation of the operator's device represented in Fig. 1 at 52. Operation of the member 52 will cause a longitudinal movement of the driving member 41 into engagement with the member 40 as above explained. When so engaged the rotation imparted to the member 41 through the connections 56, 55 and 54 will cause a corresponding rotation of the member 40 and hence of the shaft 44 and pinion 39. The pinion 39 will in turn drive the shaft 21, through the gear 19, in the direction corresponding to that in which it has theretofore been rotating, but at a considerably increased speed by virtue of the increased ratio produced by the substitution of the gears 55 and 56 in the transmission train in lieu of the gear 68.

With the increased rotative speed which is thus imparted to the member 12 (with which the member 11 has already effected engagement) the power shaft of the engine will be rotated at a speed which will assure a firing of the explosive charge and hence the starting of the engine under its own power. When so started the driving member 11 will be withdrawn by reason of the inclined formation of the jaws as shown.

The means whereby the initial transmission mechanism is rendered ineffective in part upon the introduction of the auxiliary transmission mechanism, will now be further explained. It has been stated that upon engagement of the members 41 and 40 the gear 68 is automatically eliminated from the gear train, so far as being an active force transmitting member is concerned. The gear 68 is not actually disconnected from the gear train; in fact it remains in mesh with the gear 59. Notwithstanding this continued engagement, however, the member 68 becomes ineffective although continuing to rotate. Such ineffectiveness results from the fact that there exists an increased gear ratio between gears 55 and 56 as compared with the gears 68 and 59. This greater ratio produces a rotation of the gear 59 at a speed which is a multiple of its former speed. As a result the gear 68 is caused to rotate at a speed greater than the speed of rotation of the member 65. As a result of this differential action the gear 68 becomes in effect the driving member with respect to the member 65. In consequence of this fact the clutch members 66 are held substantially in the positions shown in Fig. 2, in which positions they do not interfere with a rotation of the gear 68 at a speed substantially greater than the speed of rotation of the shaft 22 and hence of the member 65.

By reason of the construction just explained the gear 68 is rendered ineffective as a driving member with respect to the gear 59, and becomes

instead a driven member rotating at a speed greater than that of the shaft 22. Furthermore as has been made clear, the construction is such that the rotation of the members 22 and 68 at different speeds under such conditions is permitted. 5

It will be understood of course that upon the starting of the engine under its own power the operator relieves the pressure on the member 52 thereby permitting the driving member 41 to be 10 withdrawn from engagement with the member 40 by action of the spring 46.

From the foregoing it will be seen that the invention provides for the operator of the engine supplementary means for securing a successful 15 cranking of the engine in the event that the initial driving mechanism proves unsuccessful because of the lower speed thereof. By this additional means the starting of the engine on its own power is assured even in cases where starting is extremely difficult, as for example where the ignition system is of such design that a firing spark cannot be obtained except by turning the engine over at a speed at which the usual starter is incapable of taking hold because of the deceased 20 turning power which results from the use of such high rotative speeds. It is in such difficulties as this that the present invention is of great importance, in that it provides means for first taking hold on the engine member 12 by a strong 25 but relatively slow engaging force, and then provides further means for bringing the member 12 up to a more suitable cylinder firing speed. 30

It is to be understood, however, that the mechanism of the present invention is of great utility even in cases where such difficulties as that just referred to, do not exist. In fact, the economy in current consumption resulting from the use of a slow speed during starting of the motor, is an important advantage rendering the mechanism one of great utility in all cases. Of course, 35 the operator could, (if he chooses) actuate the member 52 in the first instance, and thus produce immediate actuation of the motor and starting mechanism at the higher speed, so long 40 as the conditions are such that the decreased torque at the higher speed is nevertheless sufficient to crank the engine. However, such operation will not normally be employed, if for no other reason than that it fails to take advantage 45 of the means for effecting economy in current 50 consumption.

It will be further evident from the foregoing that the present invention has the additional merit of simplicity, accessibility of the component parts, economy in arrangement and space consumption and the use of a structure wherein the necessity of shifting gears from meshing to unmeshing positions is avoided. 55

While only one embodiment of the invention 60 has been illustrated and described herein, it is to be understood that the invention may be incorporated in numerous other structures differing in form and in the method of arranging and actuating the component parts thereof. Likewise other changes, which will now appear to those skilled in the art, may be made in the form, details of construction and arrangement of the parts, without departing from the scope 65 of the invention; and reference is therefore to 70 be had to the appended claims for a definition of the limits of the invention.

What is claimed is:

1. The combination with a rotatable member of an internal combustion engine, of a substan- 75

tially constant speed motor, means responsive to energization of said motor to produce immediate operative connection between said motor and engine member whereby the latter is caused 5 to rotate at any selected one of a plurality of substantially constant speeds bearing a constant ratio to the speed at which said motor operates, and means for preventing any change in said constant ratio during the cranking operation except by manual intervention.

2. The combination with a rotatable member of an internal combustion engine, of a substantially constant speed motor, means responsive to energization of said motor to produce immediate operative connection between said motor and engine member whereby the latter is caused 15 to rotate at any selected one of a plurality of substantially constant speeds bearing a constant ratio to the speed at which said motor operates, and manually operable means permanently positioned in the mechanism for selecting the ratio 20 to be employed, said selection being possible either prior to the beginning of the cranking

operation or at any stage between the beginning and the completion thereof.

3. The method of imparting initial rotation to a rotatable member of an internal combustion engine, by the use of a substantially constant speed motor, which includes the step of causing the energization of said motor to produce immediate operative connection between said motor and engine member whereby the latter is caused to rotate at a selected one of a plurality of substantially constant speeds bearing a constant ratio to the speed at which said motor operates, the constancy of said ratio being maintained by preventing any change in said constant ratio during the cranking operation except by manual intervention, and finally the step of increasing the speed of rotation of said engine member by a definite predetermined amount, said increase being brought about by manual intervention after the initial resistance to movement has been overcome by reason of the preliminary rotation at relatively low speed.

ROMEON M. NARDONE.
